(57) **CLAIM**

The ornamental design for a part of spray dispenser, as shown and described.

DESCRIPTION

FIG. 1 is a front perspective view from above and one side of our part of spray dispenser;

FIG. 2 is a front elevational view thereof;

FIG. 3 is a rear elevational view thereof;

FIG. 4 is a side elevational view thereof;

FIG. 5 is an elevational view of the other side thereof;

FIG. 6 is a top plan view thereof; and,

FIG. 7 is a bottom plan view thereof.

The broken lines represent the boundaries of the claimed design while any other broken lines are directed to environment and are for illustrative purposes only and form no part of the claimed design.
